Primary Examiner — Catherine S Posthauer*Assistant Examiner* — Lynette Marie Sample(74) *Attorney, Agent, or Firm* — Nitin Kaushik(57) **CLAIM**

The ornamental design for a cup cover, as shown and described.

DESCRIPTION

FIG. 1 is a top perspective view of a cup cover, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top perspective view of a cup cover, shown in use with environmental subject matter of an exemplary container.

The broken lines are shown for the purpose of illustrating both parts of the cup cover as well as environmental subject matter of an exemplary container. None of the broken lines form part of the claimed design.
